CLAIM

The ornamental design for an imaging system, as shown and described.

DESCRIPTION

FIG. 1 is a top perspective view of an imaging system.

FIG. 2 is a front view of the imaging system of FIG. 1.

FIG. 3 is a back view of the imaging system of FIG. 1.

FIG. 4 is a right side view of the imaging system of FIG. 1.

FIG. 5 is a left side view of the imaging system of FIG. 1.

FIG. 6 is a top view of the imaging system of FIG. 1; and,

FIG. 7 is a bottom view of the imaging system of FIG. 1.

The broken lines depict portions of the imaging system that form no part of the claimed design.

1 Claim, 7 Drawing Sheets
